UNITED STATES PATENT OFFICE.

ELISHA BARTON CUTTEN, OF DAYTON, OHIO.

DESIGN FOR A PERMANENT MAGNET.

47,812.

Specification for Design.

Patented Sept. 14, 1915.

Application filed June 9, 1915. Serial No. 33,190. Term of patent 14 years.

To all whom it may concern:

Be it known that I, ELISHA B. CUTTEN, a citizen of the United States, residing at Dayton, in the county of Montgomery and State of Ohio, have invented a new, original, and ornamental Design for a Permanent Magnet, of which the following is a specification, reference being had to the accompanying drawing, forming part thereof.

The figure is a plan view of a permanent magnet, showing my design.

I claim:

The ornamental design for a permanent magnet, as shown.

ELISHA BARTON CUTTEN.
